UNITED STATES PATENT OFFICE.

JAMES WRIGHT, OF HAMILTON, ONTARIO, CANADA, ASSIGNOR OF THREE-EIGHTHS TO
WILLIAM SIMPSON STACEY, OF HAMILTON, ONTARIO, CANADA.

SAFETY-GUARD FOR POWER-PRESSES.

13,647.

Specification of Reissued Letters Patent. Reissued Nov. 11, 1913.

Original No. 1,067,632, dated July 15, 1913, Serial No. 710,640. Application for reissue filed October 9, 1913. Serial No. 794,355.

To all whom it may concern:

Be it known that I, JAMES WRIGHT, a citizen of the Dominion of Canada, residing at 264 Cannon street east, in the city of 5 Hamilton, in the county of Wentworth, in the Province of Ontario, Dominion of Canada, have invented certain new and useful Improvements in Safety-Guards for Power-Presses, of which the following is a specification.

This invention relates to safety guards for power presses and it has more particular reference to stamping press guards which are adapted to prevent injury to the fingers 15 or hands of the operator.

It is well known that presses of the types referred to are usually fitted with a clutch—of any appropriate type—interposed between the source of power and the crank or eccentric or other mechanism actuating the reciprocating tool, and means such as a treadle or foot lever are provided for operating said clutch so as to cause the reciprocating tool to perform its effective stroke, 20 and vice versa to throw said tool out of action when desired. Various safety guards have been heretofore suggested for use in connection, or in conjunction with the mechanism for throwing the reciprocating tool 25 into operation to effectually prevent the said tool being connected to the source of power—upon the operation of the clutch treadle for throwing said tool into action—should the fingers or hands or any part 30 thereof be in position to be crushed or injured by said tool, or in the event of any hand tool or other foreign body being accidentally placed or left in position to be crushed or touched by said safety guard or 35 tool.

The main object of my invention is to provide a safety guard, which moves or always travels slightly in advance of, and with, the reciprocating tool, and thereby 45 positively insures the operator being warned of approaching danger.

A further feature of my invention consists in arranging the movement of the protective element proper to synchronize with 50 the operation of the press, in contradistinction to devices heretofore constructed which are all brought into the protective position by the movement of the foot lever or treadle prior to the release of the clutch.

Another very important feature of my invention consists in providing safety guard for power presses which acts as a brake on the clutch and automatically and instantly stops the further movement of the reciprocating tool in the event of any obstruction 60 lying in the path of the protective element during its descent.

Another object of my invention is to provide a simple and effective means whereby for certain classes of work the operator is 65 compelled to manipulate the stock in a plane below the upper face of the lower die.

With these and other objects in view, as will more fully hereinafter appear, my invention consists in certain novel features of 70 construction, combinations, and arrangements of parts hereinafter fully described, illustrated in the accompanying drawings forming a part of this specification, and more particularly pointed out in the ap- 75 pended claims.

In the accompanying drawings, Figure 1, is a front perspective view of a stamping press fitted with one form of my improved safety guard. Fig. 2, is a similar view of 80 the same machine but taken from the rear thereof. Fig. 3, is an enlarged side elevation of the safety guard shown in connection with the press illustrated by Figs. 1 and 2, but with parts broken away or in section for the sake of clearness. Fig. 4, is a rear elevation of Fig. 3. Figs. 5 and 6, are respectively an elevation and underside plan of one of the spring controlled plungers or gripping teeth hereinafter more specifically 85 referred to. Fig. 7, is a detail side elevation of a stationary and adjustable guide bar or frame which may be used in conjunction with my invention where the stock has to be held or handled by the operator, during the 90 process of stamping or cutting, and Fig. 8, is a top plan view of the same.

Similar numerals of reference are employed to indicate corresponding parts throughout the several figures of the drawings.

According to the form of my invention illustrated more particularly in Figs. 1 to 6, and which represent one form of stamping press having my invention applied thereto, and of which presses there are several kinds, all of which can have my device readily attached thereto, small modifications

only being required in some cases to adapt said invention to the particular make of press. The stamping press for working on sheet or other metal shown in said figures 5 consists essentially of a framework or base comprising standards 1, 1; a table 2, on which the female die 3, is conveniently bolted; a male die or punch 4, carried by a vertically movable crosshead 5, which is 10 guided in guides 6, 6, on the aforesaid standards 1, 1. 7, is a horizontal shaft journaled in bearings 8, 8, at the upper ends of the standards 1, 1, and it is provided with an eccentric or crank 9, connected with 15 the crosshead, and a continuously-rotating driving wheel or pulley 10, which is mounted on one end of the shaft 7, and is coupled therewith or uncoupled therefrom by a clutch 11, all of which parts may be of any 20 usual or suitable construction. The clutch 11 is of well-known form and is fitted with the usual tripping device or dog, by means of which the plunger or crosshead 5, is coupled thereto and caused to descend and 25 ascend, and said dog is controlled by means of a connecting rod 12, coupled to the foot lever or treadle 13, which is under the action of a spiral or other suitable spring 14, in the known way. 15; is the protective 30 element or guard proper arranged, mounted and operated according to my invention as follows: This guard proper 15, may be of any suitable pattern or contour in plan to suit the male die of the press to which the 35 device is to be attached, and, it is preferably fashioned with a laterally and rearwardly projecting lug 16, to permit of its lateral adjustment on a rod 17, furnished with an eye-piece 18, for adjustable connection 40 to the lower end of an oscillatory rod 19. This oscillatory rod 19, is carried by a block or pivotally mounted piece 20, and it is furnished at its upper part with a laterally or rearwardly projecting tooth 21, for 45 the purpose hereafter to be explained. The pivotally mounted piece 20, is—as shown—preferably pivotally connected by a pin 22, to a bracket or bearing 23, conveniently secured on the press plunger. 24, is one of 50 the cross ties connecting the standards 1, 1, together. Parallel with and rearward of the aforesaid rod 19, I arrange a depending and rigidly secured rod 25, which is adapted to serve as a guide or support for adjustable blocks or stops 26, 27, the former of 55 which has hingedly connected thereto a lever 28, fitted at its free end with an anti-friction roller 29, adapted to contact with and be traversed by the aforesaid oscillatory 60 rod 19. In order to keep the roller 29, in operative engagement with the oscillatory rod 19, I fit a spring 30, one end whereof is connected to the aforesaid lever 28, and the other end is attached to an adjustable 65 collar 31, on the oscillatory rod 19. 32, is

a link or bar adjustably connected at 33, to the depending rod 25 and it is fitted at its forward end with a bent back portion 34, in which is revolubly mounted an anti-friction roller 35, which normally serves as a 70 guide for the aforesaid oscillatory rod 19, but at the same time it is so positioned as to coöperate with the stop 31, for the purpose hereafter explained. The rigid rod 25, is carried by a laterally and rearwardly projecting bracket 36, to which it is adjustably connected by lock-nuts 37, 37, at its upper end, and said bracket 36, is conveniently secured to or carried by the upper part of the aforesaid framework 1, 1. Transversely of 80 the upper part of the framework 1, 1, I mount in brackets 38, 38, a shaft or spindle 39, which serves, when the aforesaid oscillatory rod 19, is moved rearwardly on its supporting center 22, to release the clutch locking mechanism now to be described. This comprises a brake strap 40, in which are radially located a series of spring-controlled plungers or movable gripping devices 41, 41. Each of said gripping devices 41, 41, comprises a shank portion 42, (Figs. 5 and 6) of the cross-section shown by the underside plan in Fig. 6, and an extension 43, which is surrounded by a spiral spring 44, and said gripping devices are longitudinally adjustable by a lock nut or nuts 45. In the form of my invention shown these gripping devices are formed with butt ends, but in order to effectively insure more instantaneous and effective action their inner 90 ends may be toothed as shown at 46, in Figs. 5, and 6, whereby—when released—they are rendered doubly effective to arrest a further movement of the dog controlling the operation of the clutch 11, above referred to. The gripping or arresting devices 41, 41, are arranged for radial movement outward by means of a strap 47, which is adapted to be concentrically and radially moved by wiper arms 48, 48', furnished 100 with anti-friction rollers 49, 49, conveniently housed in correspondingly shaped recesses in the aforesaid brake strap 40. These wiper arms 48, 48', are connected together by a cranked arm 50, so that when 105 moved about their axes as hereafter explained, the entire series of radially disposed gripping devices 41, 41, are simultaneously raised or lowered into operative engagement with the clutch release. In order to attain this end the gripping devices are arranged to all contact with the strap or concentric piece 47, in such manner that when the wiper arms 48, 48', are raised or lowered the members 41, are simultaneously 115 and synchronously raised or lowered. 51, Figs. 3 and 4, is a detent or pawl for preventing back motion of the spindle 39, and medially of said spindle 39, I fix an arm or lever 52, which in turn is hingedly con- 120 125 130

5 nected at 53, to a rocking bar 54, provided with a depending portion 55, in which is revolvably mounted an antifriction roller 56, arranged to normally contact with the front side of the oscillatory rod 19. This rocking bar 54, is slotted at its rear part 57, to provide a clearance for the tooth 21, aforesaid and for the purpose hereafter explained.

10 58, is a stop or pin on the underside of the depending portion 55, which rests normally on the laterally and rearwardly extending bracket 36, that supports the rigid rod 25, above described.

15 59, is a lever adjustably connected at 61, to a link 62, united hingedly at its lower end 60, to a lever 63, rigidly secured to the shaft or spindle of the lower wiper 48'. Thus it will be readily seen that when the levers 60, and 63, are raised or lowered the strap 47, will be moved radially outward or inward and thereby effect the operation of the members 41, as above stated. Obviously the levers and link 60, 62, respectively may be otherwise connected so as to insure uniformity of action, and I wish it understood that I may fit one or both of said levers or link with hand grips in order to facilitate the returning of the several parts to their normal position. In order to make ready provision for accurately adjusting the brake to different sizes of presses, I provide both the lever and link 60, 62, respectively with a series of holes, 64, 64, through which the connecting pivotal pin 61, is passed as desired.

20 65, 65, are clamping studs or bolts by means of which the entire device is rigidly secured to the side of the press adjacent the clutch, and it is evident the holes through 40 which the shanks 42, of the plungers 41, pass the strap 47, are elongated to give the requisite clearance.

25 Obviously the pivotally mounted block or-piece 20, may be reversely located to the position shown and thereby render the device more sensitive; for example the parts may be so arranged that a thickness of stout paper interposed between the underface of the protective element 15, at the point 66, Fig. 3, and the upper face of the female die will be quite sufficient to cause the oscillatory rod 19, to be thrown sufficiently rearward for the projecting tooth 21, to contact either with the upper or lower rear end of 55 the rock bar 54. Instantly such contact takes place the transverse spindle 39, is turned about its axis and the lever and link 60, 62 respectively, are tripped, which throws the wipers 48, 48', past their supporting centers for the strap 47, whereupon the full force of the springs 44, 44, is brought into play and the entire set of plungers 42, are radially projected inward and jammed in the path of the clutch dog 60 and thus instantly arresting its further driving

effect or force. The action of these plungers is more than a mere clutch releasing action, for it is to be understood that the plungers exert a distinct braking and retarding effect upon the rotative element by which said dog 70 is carried and by which motion is imparted to shaft 8 in a manner well known. This part of my invention will be clear to and fully understood by all those skilled in the art to which it appertains and it will be 75 further seen that by staggering the plungers 42, as shown in Figs. 3 and 4, the device is rendered doubly sensitive. Furthermore I may cross cut or notch the nose of the clutch dog itself to render it more efficient and 80 easier engaged by one or more of the plungers 42. *Prima facie*, in very large presses the rows of plungers 42, may be multiplied in staggered relation and I wish to here point out that by actual experiments I find that 85 no matter what the size or weight of the press plunger or reciprocating part may be the device is instantly effective when the slightest obstruction lies in the downward path of the protective element or guard 15. 90 A further important point to be particularly noted in connection with my invention is the fact that the oscillatory rod 19, and guard 15, lie in planes at substantially right angles one to the other, and that the distance from the point of suspension 22, of the protective portion of said guard 15, is many times less than that of the tooth 21, to said point of suspension. Or, in other words, a very slight movement or tilting of 95 the guard 15, is considerably multiplied as regards the movement of the tooth 21. If no obstruction lies in the path of the guard 15, the oscillatory rod 19, is moved vertically up and down with the press plunger to the 100 rear of which it is connected by the bracket 23, above referred to. Once the brake device is thrown into action the press plunger is effectively stopped and cannot be moved in either direction until the operator goes 105 behind the press and raises the strap 47, by forcing up the lever 63, and its connected parts to the position shown most clearly in Fig. 3. Thus it will be clearly seen that no matter what the obstruction is in the path 110 of the protective element 15, it must be removed before further work can be operated on.

115 106, Fig. 1, is a stripper of appropriate pattern under the influence of springs 109, 120 carried by the press plunger or cross-head 5.

120 For certain classes of work it is essential that the operator handle the stock while being operated on, and in such cases I employ the device shown by Figs. 7 and 8, in combination with the guard above described. This device consists of angle pieces, the vertical links 131, whereof are slotted at 132, and they are conveniently clamped to the sides 125 of the press frame or the guides 6, 6, by set 130

4
screws 133, 133, which permit of the device being vertically adjusted. The lateral links 134, 134, of the angle pieces are turned into a horizontal plane and slotted at 135, 135, to receive clamping bolts 136, 136, which hold in place a strip 137. This device is adjusted so that the horizontal links 134, 134, are on a plane with the top face of the female die 3, with the strip 137, sufficiently in front thereof for the operator to manipulate his stock by putting his fingers below said strip. If the operator forgets and tries to handle his stock above the strip 137, the protective member 15, will be brought into operation and trip the clutch locking brake before any damage or injury can be brought about.

15 Obviously the angle pieces may be inverted and clamped to the table 2, of the press, without departing from the spirit and scope of my invention.

20 This rigid attachment is particularly useful for cases where the operator is working on cup-shapes having holes punched in their sides when it is necessary for said operator to hold the cup shape in place. In such cases the strip 137, will be set so as to compel the operator to handle his work from under said strip 137, where his hands will be safe and free from any chance of injury. If he 25 should forget and put his hand or fingers over the strip 137, he will be struck by the descending stripper 106, or guard 14, when the press will be instantly stopped as above set forth. The top edge of the strip 137, 30 will never be arranged or adjusted below the face of the lower die thereby rendering it impossible to get the fingers over the guard and under the punch proper.

35 The operation of my improved safety guard is briefly as follows:—As the punch 4, descends, the guard 15, and, or stripper 106, will travel slightly in advance thereof. If there be no obstruction encountered said guard 15, and, or stripper 106, will be lifted 40 when it contacts with the lower die 3. This movement will synchronize with the stop 31, contacting with the arm 32, whereupon the rod 19, will be allowed to tilt rearwardly in the slot 57, without engaging the rock bar 54, that releases the clutch brake 40.

45 From the foregoing description and accompanying drawings it will be readily seen that by my invention I provide an extremely effective and reliable device for the purposes set forth, while at the same time in no way interfering with the utility or efficiency of the press, all that is necessary being the tapping of three or four holes and insertion of set screws to attach the entire device in position.

50 Obviously my invention may be readily adapted to any type of stamping press or machine having a reciprocating tool worked or operated by a clutch release mechanism, 55 as all parts are made relatively adjustable

and I wish it clearly understood that I do not confine myself to the specific arrangements and combinations of parts illustrated and described, various alterations in their form and the arrangement thereof being possible without in any way departing from the spirit and scope of the invention, and it is intended fully to include all such within the present application, and as limited by the appended claims.

70 Having thus described my invention, what I claim as new and desire to secure by Letters Patent, is:—

75 1. In a safety guard for stamping presses, the combination with a driving member of the press, of a brake element, a guard element, and means for causing said brake element to engage said driving member of the press when said guard element encounters an obstruction.

80 2. In a safety guard for stamping presses, the combination with a driving member of the press, of a toothed brake member, a guard element, and means for causing said toothed brake member to engage said driving member of the press when said guard 85 element encounters an obstruction.

85 3. In a safety guard for stamping presses, the combination with a driving member of the press, of a brake element, a guard element, means for causing said brake element to engage said driving member of the press when said guard element encounters an obstruction, said brake member comprising a plurality of radially disposed members, and a connecting strap for all of said radially disposed members, whereby all of said 90 radially disposed members are moved simultaneously to and from operative position.

95 4. In a safety guard for stamping presses, the combination with a driving member of the press, of a brake element, a guard element, means for causing said brake element to engage said driving member of the press when said guard element encounters an obstruction, said brake element comprising a plurality of radially disposed spring actuated plungers, and a strap through which 100 all of said plungers pass.

105 5. In a safety guard for stamping presses, the combination with a driving member of the press, of a brake element, a guard element, means for causing said brake element to engage said driving member of the press when said guard element encounters an obstruction, said brake element comprising a plurality of radially disposed spring actuated plungers, and a strap through which 110 all of said plungers loosely pass.

115 6. In a safety guard for stamping presses, the combination with a driving member of the press, of a brake element, a guard element, means for causing said brake element to engage said driving member of the press when said guard element encounters an ob- 120

struction, said brake element comprising an arcuate member, a plurality of radially disposed plungers passing through said arcuate member, springs for forcing said plungers inwardly, and a strap through which all of said plungers pass.

7. In a safety guard for stamping presses, the combination with a movable press member, of a braking mechanism, a press driving element upon which said braking mechanism acts, a controlling member for said braking mechanism, and a guard carrying element movable bodily with the movable press member and pivotally mounted upon said press member and engaging and actuating said controlling member when tilted out of normal alinement.

8. In a safety guard for stamping presses, the combination with a movable press member, of a restraining mechanism, a press driving element upon which said restraining mechanism acts, a controlling member for said restraining mechanism, and a guard carrying element movable bodily with the movable press member and engaging and actuating said controlling member when tilted out of normal alinement by the contact of the guard with an obstruction.

9. In a safety guard for stamping presses, the combination with a movable press member, of a braking mechanism, a press driving element upon which said braking mechanism acts, a controlling member for said braking mechanism, and a guard carrying element movable bodily with the movable press member and pivotally mounted upon said press member and engaging and actuating said controlling member when tilted out of normal alinement by the contact of the guard with an obstruction, said braking mechanism comprising a plurality of radially disposed members.

10. In a safety guard for stamping presses, the combination with a movable press member, of a braking mechanism, a press driving element upon which said braking mechanism acts, a controlling member for said braking mechanism, a guard carrying element movable bodily with the movable press member and pivotally mounted upon said press member and engaging and actuating said controlling member when tilted out of normal alinement by the contact of the guard with an obstruction, said braking mechanism comprising a plurality of radially disposed spring pressed members.

11. In a safety guard for stamping presses, the combination with a movable press member, of a braking mechanism, a press driving element upon which said braking mechanism acts, a controlling member for said braking mechanism, and a guard carrying element movable bodily with the movable press member and pivotally mounted upon said press member and engaging

and actuating said controlling member when tilted out of normal alinement by the contact of the guard with an obstruction, said braking mechanism comprising a plurality of radially disposed toothed plungers.

12. In a safety guard for stamping presses, the combination with a movable press member, of a braking mechanism, a press driving element upon which said braking mechanism acts, a controlling member for said braking mechanism, a guard carrying element movable bodily with the movable press member and pivotally mounted upon said press member and engaging and actuating said controlling member when tilted out of normal alinement by the contact of the guard with an obstruction, said braking mechanism comprising a plurality of radially disposed spring pressed members, and a common actuating member for all of said plungers.

13. In a safety guard for stamping presses, the combination with a movable press member, of a braking mechanism, a controlling member for said braking mechanism, a press driving element upon which said braking mechanism acts, a guard carrying element movable bodily with the movable press member and pivotally mounted upon said press member and engaging and actuating said controlling member when tilted out of normal alinement by the contact of the guard with an obstruction, said braking mechanism comprising a plurality of radially disposed toothed plungers, and a common actuating member for all of said plungers.

14. In a safety guard for stamping presses, a restraining brake comprising an arcuate member, a plurality of radially disposed brake elements, means for actuating said elements in one direction, a press actuated member for actuating said elements in the opposite direction and against the tension of said means.

15. In a safety guard for stamping presses, a restraining brake mechanism comprising an arcuate member, a plurality of radially disposed spring pressed plungers mounted therein, a common actuating strap for all of said plungers, cranks arranged adjacent each end of said strap and arranged when actuated to move said strap against the tension of said springs, and a member for actuating said cranks simultaneously.

16. In a safety guard for stamping presses, a restraining brake mechanism comprising an arcuate member, a plurality of radially disposed spring pressed plungers mounted therein, a common actuating strap for all of said plungers, cranks arranged adjacent each end of said strap and arranged when actuated to move said strap against the tension of said springs, a mem-

ber for actuating said cranks simultaneously, a guard carrying element bodily movable with and pivoted upon the press plunger, and means for actuating said cranks when said guard carrying element is swung out of normal alinement by contact with an obstruction.

17. In a device of the character described, the combination with a vertically movable press plunger, of a rod pivotally mounted thereon and bodily movable therewith, a guard element carried by said rod, a restraining brake, an actuating member for said brake through which said rod travels, the tilting of said rod upon its pivotal point when the guard strikes an obstruction serving to move said brake actuating member.

18. In a device of the character described, the combination with a press and its vertically movable tool carrying member, of a guard carrying rod pivotally mounted upon said plunger and bodily movable therewith, a guard carried by said guard carrying rod, a restraining brake mechanism, an operating member for said brake mechanism, said guard carrying rod traveling in a cut out portion of said operating member, and a projection carried by said rod and adapted to engage and actuate said brake controlling member when the guard carrying rod is tilted upon its pivot.

19. In a device of the character described, the combination with a restraining brake, of a controlling member therefor, a guard carrying rod passing through said controlling member and movable in a cut out portion thereof, a block pivotally mounted upon the press plunger and through which said guard carrying member passes, and a guard carried by said guard carrying member.

20. In a device of the character described, the combination with a restraining brake, of a controlling member therefor, a guard carrying rod passing through said controlling member and movable in a cut out portion thereof, a block pivotally mounted upon the press plunger and through which said guard carrying member passes, and a guard carried by said guard carrying member, said guard lying substantially at right angles to the guard carrying member.

21. In a device of the character described, the combination with a restraining brake, of a guard carrying rod pivotally mounted upon the press plunger and bodily movable therewith, a guard carried by said guard carrying rod, a controlling member for the brake mechanism, an anti-friction roller car-

ried by said controlling member and bearing against the guard carrying rod, a fixed member, a lever pivotally mounted thereon, an anti-friction roller carried by said lever bearing upon the guard carrying rod, and a spring connection between said lever and said guard carrying rod.

22. In a device of the character described, the combination with a restraining brake mechanism of a shaft mounted upon a fixed portion of the press frame, a horizontally disposed controlling member, an arm carried by said shaft to which one end of said controlling member is pivoted, and means actuated by said shaft for controlling the brake mechanism.

23. In a device of the character described, the combination with a restraining brake mechanism, of a shaft mounted upon a fixed portion of the press frame, a horizontally disposed controlling member, an arm carried by said shaft to which one end of said controlling member is pivoted, means actuated by said shaft for controlling the brake mechanism, a guard carrying rod, a guard carried by said rod, and means carried by said rod for actuating said controlling member when said rod is tilted out of vertical alinement.

24. In a device of the character described, the combination with a restraining mechanism, of a shaft mounted upon a fixed portion of the press frame, a horizontally disposed controlling member, an arm carried by said shaft to which one end of said controlling member is pivoted, means actuated by said shaft for controlling the brake mechanism, a guard carrying rod, a guard carried by said rod, and means carried by said rod for actuating said controlling member when said rod is tilted out of vertical alinement, said rod being pivotally mounted upon and traveling with the press plunger.

25. In a device of the character described, the combination with a stamping press, of a vertically movable guard, and a fixed member arranged in such position that the stock must be handled therebeneath and so keep the fingers of the operator out of the path of said guard.

Signed at Hamilton, Ontario, Canada, this 6th day of October 1913.

JAMES WRIGHT.

In the presence of—

ALFRED T. BRATTON,
GERTIE NICHOLSON.
